WILLIAM A. STARK AND DAVID A. CRAIG, OF PHILADELPHIA,
PENNSYLVANIA.

DESIGN FOR A GAME-BOARD.

SPECIFICATION forming part of Design No. 31,657, dated October 10, 1899.

Application filed August 7, 1899. Serial No. 726,475. Term of patent 3½ years.

To all whom it may concern:

Be it known that we, WILLIAM A. STARK and DAVID A. CRAIG, citizens of the United States, residing in the city and county of Philadelphia, State of Pennsylvania, have invented and produced a new and original Design for Game-Boards, of which the following is a specification, reference being had to the accompanying drawings, forming part thereof.

10 The leading feature of our design for a game-board is a board having concentric circles, lines intermediate said circles, and fields exterior to said circles.

Figure 1 represents a plan view of a game-board embodying our design. Fig. 2 represents a section on line x x , Fig. 1.

In the drawings, A designates a game-board, and B and C concentric circles.

D designates lines intermediate said circles, and E fields exterior to said circles.

Having thus described our invention, what we claim as new, and desire to secure by Letters Patent, is—

The design for a game-board substantially as shown and described.

WILLIAM A. STARK.
DAVID A. CRAIG.
